ELECTRIC SWITCH

Filed Nov. 11, 1922

Inventor:
John D. Hilliard,
by *Wm. D. Lantz*
His Attorney.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed November 11, 1922. Serial No. 600,200.

My invention pertains to electric switches and in particular to improved means for accelerating the opening of the current rupturing contacts of such switches.

5 In electric switches of the fluid break type, when the contacts are separated, an arc is drawn in the liquid and part of the liquid is vaporized and disassociated, suddenly producing gases at such high pressure as to 60 stress the tank of the switch. The amount of gases formed and consequently the pressure generated depends, among other things, on the length of time during which the arc is maintained. This time will be largely de- 65 10 15 20 25 30 35 40 45 50 55 60 65 70 75 80 85 90 95 100 105 110

One object of my invention is therefore to provide in an electric switch improved means for accelerating the movement of the circuit interrupting contacts.

Another object of my invention is to provide in an electric switch improved means for limiting the gas formation when an arc 25 is drawn in a liquid upon the opening of the separable contacts.

A further object of my invention is to provide improved means for locking the contacts of an electric switch against the magnetic repulsion caused by the current flowing through said contacts.

Other objects and advantages will appear from the following description of my invention when taken in connection with the accompanying drawing, in the single figure of 35 which is illustrated a single pole switch of the fluid break type shown partly in elevation and partly in section, some of the parts being broken away.

40 Referring more particularly to the drawing, there will be seen a switch frame 1 adapted to support insulating bushings 2 which are held in place by clamping plates 3. Stationary electrodes 4 pass through and are fastened to the insulating bushings 2. The stationary electrodes 4 are adapted to support primary contact brushes 5 and secondary contact members 6.

45 A tank 7 having an insulating lining 8 is supported from the switch frame 1 and is adapted to contain an insulating liquid 9, the normal height of which is indicated by the shading.

50 A link 10 is connected with any suitable operating means (not shown but which may

for example be similar to that shown in U. S. Letters Patent No. 942,491, to W. L. R. Emmet and E. W. Hewlett dated Dec 7, 1909) and the toggle 11 to produce movement of a contact lever 12 to which an operating rod 13 is connected. The operating rod 13 passes through an aperture 14 in the switch frame 1 and supports a primary bridging member 15 to open or close the circuit at the primary brushes 5. Rods 16, 65 60 65 70 75 80 85 90 95 100 105 110

An insulating secondary contact support 18 is attached to the switch frame 1 and is arranged to pivotally support the secondary contact members 19. Electrical connection 75 between the secondary contact members 19 is maintained by a flexible connection 20. Pins 21 attached to the accelerating members 16 are adapted to engage the secondary contact members 19. The movable secondary contact members 19 are adapted to engage with the secondary contact members 6.

The secondary contact levers 19 are maintained in closed position by means of a restraining block 22 fixed to an extension 23 85 80 85 90 95 100 105 110

of the operating rod 13 and adapted to operate with one end of each of these levers. The springs 24 provide a resilient connection between the secondary contact levers 19 and the accelerating members 16. Operation from the closed position of the switch follows: Automatic or manual tripping of the operating means causes downward movement of the operating rod 13 breaking contact between the primary brushes 5 and the primary bridging member 15, the secondary contact members 19 being held in engagement with the secondary contact members 6 by the pressure of springs 24 and restraining block 22 until the restraining block 22 has cleared the lower ends of the secondary contact members. Further movement of the operating rod 13 will cause the pins 21 in the accelerating member to engage with the secondary contact members 19 and cause their disengagement with the secondary contact clips 6 to make the final break in the circuit.

The primary brushes 5 are usually made of strips of copper or copper alloy which 110

has a low elastic limit and the resiliency of which may be destroyed by heating due to brush contact resistance. With the disclosed arrangement of parts, the magnetic field, produced by the current flowing through the switch, acts to force the primary contacts 5 downwardly into engagement with the bridging member 15. This is of particular advantage in that it insures good contact and prevents heating of the brushes.

The secondary contact members 19 are locked in closed position against the action of the magnetic field of the switch by means of the member 22 and are operated in response to downward movement of the primary bridging member 15. Due to the fact that the actuating force is applied to the members 19 at a point near their pivotal connection with the fixed insulating member 18, the contacting parts of these members are moved at a speed greatly in excess of that at which the primary bridging member itself moves. This serves to quickly break the circuit and prevent the formation of destructive arcs.

In closing, the springs 24 which are under compression between the accelerating members 16 and the secondary contact members 19 cause the secondary contact members to follow the upward movement of the accelerating members and clear the passage for the restraining block 22 to enter between the lower ends of the secondary contact members 19 and lock them in the closed position. Further upward movement of the operating rod 13 will establish a primary circuit by the engagement of the primary brushes 5 with the primary bridging member 15.

My invention may be embodied in other forms than that shown and described, and is, therefore, not restricted to the construction shown but comprises all changes and modifications which come within the spirit and scope of my invention as indicated by the appended claims.

What I claim as new and desire to secure by Letters Patent of the United States, is,—

1. In a switch, a plurality of stationary contact members, a movable bridging contact member, pivotally mounted secondary contact members, means associated with said bridging member for moving said secondary contact members to closed circuit position and for locking the same in said position, and means movable with said bridging member in its circuit opening movement for engaging said secondary contact members at points adjacent their pivotal centers for

rapidly moving said members to open circuit position.

2. An electric switch comprising a pair of fixed main contacts, a bridging member adapted to engage said contacts, a pair of fixed secondary contacts, movable contact members connected together and arranged to bridge said secondary contacts, and a locking member movable with said bridging member, said locking member being arranged to have sliding engagement on opposite sides with said contact members when the bridging member is initially moved from closed circuit position for holding the contact members locked in closed circuit position.

3. An electric switch comprising fixed main contacts, a bridging member adapted to engage said contacts, an operating member therefor, fixed secondary contacts, a support, a pair of secondary contact arms pivoted thereto at fixed points, an operating connection between the bridging member and each of the secondary contact arms, and a locking member operatively connected to the bridging member for locking the contact arms in closed circuit position, said locking member having a limited movement while maintaining the contact arms in locked circuit closing position.

4. An electric switch comprising fixed main contacts, a bridging member adapted to engage said contacts, an operating member therefor, fixed secondary contacts, a support, a pair of secondary contact arms pivoted to the support at fixed points and adapted to engage said secondary contacts, said contact arms having locking extensions thereon, and a locking member movable with said bridging member and having sliding engagement with said extensions for holding the arms in contact with the fixed secondary contacts throughout a predetermined range of movement of the bridging member.

5. An electric switch comprising fixed main contacts, a bridging member adapted to engage said contacts, an operating member therefor, fixed secondary contacts, a support, a pair of spaced secondary contact arms pivoted thereto and each having a locking extension, and a locking member carried by the bridging member between said locking extensions and arranged to maintain said extensions in spaced relation when the bridging member is in a predetermined position, thereby locking the contact arms in contact with the fixed secondary contacts.

In witness whereof, I have hereunto set my hand this 9th day of November, 1922.

JOHN D. HILLIARD.
